(57) **CLAIM**

The ornamental design for a pinless articulated band, as shown and described.

DESCRIPTION

FIG. 1 is a perspective view showing a lineal segment of the pinless articulated band of my new design;

FIG. 2 is a top view thereof;

FIG. 3 is an end view thereof;

FIG. 4 is a side elevational view thereof; and,

FIG. 5 is a perspective view of the pinless articulated band of my invention in the configuration of an endless band.
